ABSTRACT: The compound having formula:

wherein, R represents alkyl having one to six carbon atoms and X represents hydrogen, halogen, alkyl having one to three carbon atoms or alkoxy having one to three carbon atoms and n is an integer of 0-5 prepared in accordance with the following equation:

wherein M represents hydrogen or metal atom and m represents valency of M and R, X and n, each have the aforesaid meanings. The novel compounds have superior acaricidal activities without mammalian toxicity.

O-ACYLBENZOHYDROXAMATES

THE DETAILED EXPLANATION OF THE INVENTION

This invention relates to novel O-acylbenzohydroxamates having acaricidal activity and to a novel process for the preparation of the same.

The novel compounds in the present invention are characterized by the formula (I)

(I)

wherein R represents alkyl having one to six carbon atoms and X represents hydrogen, halogen, alkyl having one to three carbon atoms or alkoxy having one to three carbon atoms and n is an integer of 0-5.

Those compounds possess acaricidal activities against phytophagous mites including various mites which have become resistant to organo phosphate and 2,4,5,4'-tetrachlorodiphenyl sulfone which have up until now been used widely in mite control.

The compounds of the invention have low mammalian toxicity.

The compounds in this invention can be prepared in accordance with the following equation.

wherein M represents hydrogen or metal atom and m represents valency of M and R, X and n each have the aforesaid meanings.

Usually the process of the invention is carried out in a suitable inert solvent at a temperature of about -20°-100° C. and the reaction is completed in between 2 hours and 10 hours.

In the case where the calcium, silver, zinc, copper (cuprous, cupric) or iron (ferrous, ferric) salt of compound II is used, the reaction is preferably carried out in low polar solvent such as benzene, toluene, xylene or tetrachloromethane at a temperature of about 20°-100° C.

Further, when an alkali metal salt such as a sodium or potassium salt of compound (II) is employed in the reaction, high polar solvent such as acetone, methyl ethyl ketone, cyclohexanone, acetonitrile or tetrahydrofuran is preferably employed at a temperature of about -20°-0° C.

When an alkylhydroxamate is used as the starting material, the reaction can be promoted at a temperature of about -20°-0° C. by use of a base such as sodium hydroxide. Water has a tendency to decrease the yield of the products (I), so generally the introduction of water into the reaction mixture is to be avoided, however, if necessary, the minimum quantity of water may be used, for example, if necessary to dissolve the alkali metal hydroxide, a small portion of water may be added.

Furthermore a little amount of an amino compound such as triethyl amine can be added as a catalyst.

After the reaction is terminated, the products (I) are isolated from the reaction mixture by employing the well-known procedures. For example, in case of the reaction in a non or

low polar solvent, after filtering off the metal chloride crystals present, sodium hydroxide is added to the filtrate and unreacted starting materials and by-products of the organic acids present are extracted into the sodium hydroxide layer. The upper solvent layer is separated off and dried, and the solvent is distilled off. The product (I) is obtained in the form of crystals or oil, having a high degree of purity more than 80 percent, about 20 percent or less of impurity is an N-acyl compound which is a main byproduct.

10 The product (I) has geometrical isomers which can be distinguished by their Infrared Spectrum absorptions. The ratio of the various isomers depends the reaction conditions.

One isomer has been named the "α-isomer" and the other the "β-isomer" in consideration of different physical properties and observation of Infrared Spectrum absorption in the position of 9μ wavelength. FIG. 1-6 show the Infrared Spectrum absorptions of the product (I) in tetrachloromethane. FIG. 1 shows the α-isomer and FIG. 2 shows the β-isomer of compound No. 5 in Table I. FIG. 3 is the infrared absorption spectrum of an α-isomer and FIG. 4 of the β-isomer of compound No. 6 in the same table. FIG. 5 shows the spectrum of the α-isomer and FIG. 6 the β-isomer of compound No. 7 in the table.

25 In order to facilitate a clear understanding of the invention, the following preferred specific embodiments are described.

EXAMPLE 1

30 preparation of

35

A. To a suspension of 70 g. (0.188 mole) of a silver salt of ethyl 3,6-dichloro-2-methoxybenzohydroxamate in 350 ml. of benzene, toluylchloride 29 g. (0.188 mole) was added and the mixture stirred at about 50° C. for 6 hours.

40 After termination of the reaction, silver chloride was filtered off and the filtrate was washed with 100 ml. of 2 percent sodium hydroxide aqueous solution to remove the impurities and then washed with water and dried.

45 The resulting benzene solution was distilled to remove benzene and 69.2 g. of oily matter (consists of α-isomer and a little amount of byproduct of N-acyl compounds) were obtained as the residue.

50 The oily matter is gradually crystallized at room temperature, and the crystals were recrystallized from ligroin-petroleum ether to obtain the pure crystals of α-isomer, m.p. 82.5°-83.5° C.

B. A mixture of 88.5 g. (0.3 mole) of copper salt of ethyl 2,6-dichloro-2-methoxybenzohydroxamate and 42 g. (0.3 mole) of toluylchloride in 800 ml. of benzene was stirred at 50° C. for 4 hours. 90 g. of oily matter substantially consisting of β-isomer were obtained after a working up similar to example 1 (A). The recovered product was purified by chromatography on silica gel column using acetone-n-hexane as eluent to obtain pure crystals, of β-isomer m.p. 37°-38° C.

EXAMPLE 2

65 preparation of

70

To a solution of 10.6 g. (0.04 mole) ethyl 3,6-dichloro-2-methoxybenzohydroxamate and 6.2 g. (0.04 mole) of toluylchloride, 6.2 g. in 110 ml. of acetone cooled at -10° C., 6 ml. (0.04 mole) of 30 percent sodium hydroxide aqueous

solution was added in dropwise fashion for about a half hour and the mixture was stirred for 2 more hours at the same temperature.

After the termination of the reaction, the temperature was gradually raised to room temperature and then the acetone was distilled off.

Forty ml. of chloroform and 20 ml. of 2 percent sodium hydroxide aqueous solution were added to the residue and the resulting mixture was shaken whereby the byproduct was extracted into the water layer. The chloroform layer was evaporated to obtain 15 g. of oily matter comprising mainly the β -isomer of ethyl O-tolyl-3,6-dichloro-2-methoxybenzohydroxamate and a little amount (about 7 percent) of byproduct (N-acyl compound).

The reaction was purified by chromatography on silica gel column using acetone-n-hexane as eluent to obtain pure crystals of β -isomer, m.p. 38°-37°C.

EXAMPLE 3

preparation of

10.6 g (0.04 mole) of ethyl 3,6-dichloro-2-methoxybenzohydroxamate, 6.2 g

10.6 g. (0.04 mole) of ethyl 3,6-dichloro-2-methoxybenzohydroxamate, 6.2 g. (0.04 mole) of toluylchloride and

5 0.35 mg. of triethylamine (catalyst) were dissolved into 250 ml. of chloroform. To the solution cooled to about 0°C., 6 ml. (0.04 mole) of 30 percent sodium hydroxide aqueous solution was gradually added for about 15 minutes and the mixture was

10 stirred for 2 hours at the same temperature. After the termination of the reaction, the temperature was gradually raised to room temperature. The chloroform layer was washed with 20 ml. of 2 percent sodium hydroxide aqueous solution in order to remove byproduct and washed with water and dried.

15 The resultant chloroform solution was evaporated to obtain an oily residue comprising mainly the α -isomer, of ethyl O-tolyl-3,6-dichloro-2-methoxy hydroxamate m.p. 82.5°-83.5°C. and a little amount (about 8 percent) of byproduct N-acyl compound.

20 In addition to the above mentioned compounds described in the preceding examples, some typical compounds of the present invention are listed in table I.

25 These examples and table I include merely some of the compounds of the present invention, so that the scope of the present invention is not limited only to those compounds listed in table I.

TABLE I

No. of compound	Chemical structure	Chemical name	M.P. or refractive index
			α -isomer, °C. β -isomer, °C.
1-----		Methyl O-benzyl-3,6-dichloro-2-methoxybenzohydroxamate.	99-100 (1)
2-----		Methyl O-tolyl-3,6-dichloro-2-methoxybenzohydroxamate.	98-99 (1)
3-----		Methyl O-(4-chlorobenzyl)-3,6-dichloro-2-methoxybenzohydroxamate.	104-105 (1)
4-----		Methyl O-(4-nitrobenzyl)-3,6-dichloro-2-methoxybenzohydroxamate.	109-110 -----
5-----		Ethyl O-benzyl-3,6-dichloro-2-methoxybenzohydroxamate.	87-88 70-71
6-----		Ethyl O-(3,6-dichloro-2-methoxybenzyl)-3,6-dichloro-2-methoxybenzohydroxamate.	84-85.5 95-96

TABLE I -Continued

No. of compound	Chemical structure	Chemical name	M.P. or refractive index	
			α -isomer, °C.	β -isomer, °C.
7		Ethyl O-tolyl-3,6-dichloro-2-methoxybenzohydroxamate.	82.5-83.5	37-38
8		Ethyl O-(4-chlorobenzoyl)-3,6-dichlorohydroxamate.	70-71	-----

¹ Crude product viscous oil.

It is the advantages of the invention that the compounds listed in table I possess acaricidal activity and have no phytotoxicity. Usually, a small but effective amount of the compounds are applied at a concentration of 0.0125 to 0.05 percent on plants to combat and eradicate the pests. The concentrations of the active compounds in the compositions are varied by kinds of the formulation used, they may be used in a range of 10-80 percent, preferably 20-60 percent in the wettable powder, 0.5-50 percent, more preferably 20-40 percent in the emulsifiable concentrate and 1-10 percent in the dust. The nonlimiting example of the composition of the invention are illustrated as follows:

Example 4: Wettable powder

	Parts by weight
Compound 5	20
Higher alcoholsulfonates	5
Diatomaceous earth	75

These were mixed and micronized in jet pulverizer to a particle size of 4-20 micron.

In practical use, the micronized mixture was diluted with water in a concentration of 0.01 to 0.05 percent of active ingredient water. The suspension was applied as a spray.

Example 5: Emulsifiable concentrate

	Parts by weight
Compound 7	8
Alkylarylpolyoxyethylene	7
Dimethylformamide	45
Toluene	40

These were mixed and dissolved. In practical use, this solution was diluted with water in a concentration of 0.01 to 0.05 percent of active ingredient and this suspension was sprayed.

Example 6: Dust formulation

	Parts by weight
Compound 5	5
Alkylarylpolyoxyethylene	0.1
Talc	94.9

These were mixed and crushed in fine powder. The dust formulation was applied as dusting at rate of 4 to 5 kg. per acre.

In the examples 3 to 5, the emulsifying, wetting or dispersing agents, carriers and solvents disclosed are not to be limited by the examples given.

Mammalian toxicity of the typical compound, for example, compound 5 is 2000 mg./kg., compound 8 is 3000 mg./kg. as the value of acute oral LD₅₀ for mice.

EXAMPLE 7

Acaricidal activity for 2,4,5,4'-tetrachloro diphenyl sulfone resistant citrus red mite are shown in table II.

Mandarin orange leaves, on which the living adult female mites (*Panonychus citri*) were laid, were put into petri dishes, the dead mites were removed after one day of treatment with a

water suspension containing 0.05 percent of the compound formulated in emulsifiable concentrate by spraying. After 3 days of spraying, adult mortalities were counted, and the surviving adult mites were removed. The viability of eggs deposited during this period was examined after 15 days of the removal of the surviving adult mites.

$$30 \quad \text{Mortality (percent)}: \frac{(a-b)}{a} \times 100$$

a: numbers of living mites in untreated plots
b: number of surviving mites in treated plots

$$35 \quad \text{Ovicidal activity (percent)}: \frac{(a'-b')}{a'} \times 100$$

a': numbers of eggs deposited
b': numbers of hatched eggs

TABLE II

No. of compound:	Adult mortality (percent)	Ovicidal activity (percent)
5	100	100
7	100	100
8	100	100
	37	42
Phenkapton (control)		

EXAMPLE 8

5 Residual effect on citrus red mite.

Water suspensions containing 0.03 percent or 0.015 percent of the specified compound were sprayed on leaves of Summer orange (*Citrus Aurantium* nat sudaidai Makino et Nemoto). No phytotoxicity was observed. After 4 days and 23 days the leaves were picked off and were put into glass plates and adult female mites were inoculated. After 3 days for inoculation, adult mortalities were counted and residual effect was investigated.

65 The result was shown in table III.

TABLE III

No. of compound:	Content of compound in suspension (percent)	Residual effect (percent) after	
		4 days	23 days
5	0.03	100	100
	0.015	100	100
7	0.03	100	100
	0.015	100	100
1,1-bis(p-chlorophenyl)-2,2,2-trichloromethanol (control)	0.02	100	0

We claim:

1. An O-acylbenzohydroxamate compound of the formula:

wherein, R represents alkyl having one to six carbon atoms and X₁, X₂ and X₃ each represent a member selected from the group consisting of hydrogen, halogen, NO₂, alkyl having one to three carbon atoms or alkoxy having one to three carbon atoms.

2. A compound according to claim 1 having the formula

3. A compound according to claim 1 having the formula

4. A compound according to claim 1 having the formula

5. A compound according to claim 1 having the formula

10 6. A compound according to claim 1 having the formula

20 7. The compound of the formula:

25 8. The compound of the formula:

30 9. The compound of the formula:
